UNITED STATES PATENT OFFICE.

FRIEDRICH W. OELSCHLAEGER, OF WATERTOWN, WISCONSIN.

BUILDING-BLOCK.

No. 854,708.

Specification of Letters Patent.

Patented May 21, 1907.

Application filed February 12, 1906. Serial No. 300,651.

To all whom it may concern:

Be it known that I, FRIEDRICH W. OELSCHLAEGER, a citizen of the United States, residing at the city of Watertown, in the 5 county of Jefferson and State of Wisconsin, have invented certain new and useful Improvements in Building-Blocks; and I do hereby declare the following to be a clear and exact description of the invention, such 10 as will enable others skilled in the art to which it pertains to make and use the same, reference being had to the accompanying drawings, which form a part of this specification.

15 The purpose of this invention is to provide an improved building-block of tile, concrete, or the like material, affording a better protection against frost and having other structural advantages not afforded by concrete 20 building blocks heretofore made, as herein-after described and claimed.

Referring to the accompanying drawing, Figure 1 is a perspective view of a building block embodying my invention. Fig. 2 is a 25 plan view of the top of the block. Fig. 3 is a side view of the block. Fig. 4 is a vertical sectional view of a wall constructed of building blocks embodying my invention, taken at line A A, Fig. 2. Fig. 5 is a side 30 elevation of a wall, constructed of building blocks embodying my invention, part being in section at line B B, Fig. 2.

Referring to the accompanying drawing, there is shown a concrete block with a plurality of apertures, oblong in horizontal section, extending vertically through the block, of which apertures 1 and 2 are of unequal 35 length, so arranged that when blocks are placed in wall, joints broken at halves as is customary in ordinary construction of walls, a continuous airspace will be formed, as 40 illustrated in Fig. 4. Apertures 3 3 are of equal length so arranged that when blocks are placed in wall, joints broken at halves as 45 is customary in ordinary construction of walls, will register to form vertical airspaces throughout the height of the wall independent of the continuous airspace formed by apertures 1 and 2 heretofore described.

50 The transverse webs 4 and 5, connecting the outside walls 11 of the block with an intermediate or central web 12, of which rib 6, forms a part and in which is located recess 7, are of staggering arrangement to make the 55 path for frost to penetrate the wall as long as

possible. Each block is provided with a rib 6 projecting and running along one edge of said central web extending the length of said web, and along one end of the block, in both cases to a point where the recess or groove 7, 60 begins, which recess or groove 7 is cut into and extends along the opposite side of said central web and along the opposite side or end of said block, being so located that when the blocks are put in position in wall, said 65 rib 6 will fit into recess 7. Rib 6 only projects one half of the depth of recess 7 and thereby when put in position in wall will form a continuous airspace, at right angles, 70 encircling each block at the central portion thereof as illustrated in Fig. 5. This airspace is particularly of great value to take care of any moisture that may form by reason of unequal temperature on the inside and outside of the structure, thus arresting dampness that would otherwise affect the inside of 75 a building wall in particular.

The ends of the block are closed and therefore of greater strength than so called open-end apertures which are easily broken off by 80 ordinary handling. The corrugations 8 on ends of block are to give the mortar the largest possible binding surface. The continuous airspace formed by apertures 1 and 2 as illustrated in Fig. 4 has the advantage over single, vertical airspaces in that, it will prevent 85 the breaking of the block by accumulation of gases within the wall, for which reason single, vertical air spaces are objectionable. Another advantage is,—the web, 5, and the end 90 webs 9 and 10, are totally encircled by air, by reason of apertures 1 and 2, thereby making it almost impossible for frost to penetrate to the inside of the wall. In the construction of a wall it is preferable to use the block so that 95 airspaces 1 and 2 will be toward the inside of building, however this is not necessary.

What I claim as my invention and desire to secure by Letters Patent, is—

1. The herein-described building block 100 comprising side walls, an intermediate longitudinal web, and a plurality of transverse webs, there being formed by said walls and webs a plurality of vertical air spaces, the said intermediate web having a projecting 105 rib extending along one end and one edge thereof and also having a groove extending along the opposite end and edge thereof to receive the ribs of adjacent corresponding blocks, and the groove being deeper than the 110

depth of the rib whereby there is formed an additional air space extending longitudinally and vertically of the block.

2. A building wall construction embodying a plurality of similar blocks, each of said blocks comprising side walls, an intermediate longitudinal web, and a plurality of transverse webs, whereby a plurality of vertical air spaces are formed and certain air spaces of one block being in register with certain other air spaces of the blocks next above and below, said intermediate web having a rib pro-

jecting therefrom along one end and one edge thereof and also having a groove in the opposite end and edge thereof to receive the ribs of adjacent blocks, the said groove being deeper than the said rib whereby there is formed an air space surrounding each of the several blocks. 15
